(57) **CLAIM**

The ornamental design for a “floatable screen and suction device,” as shown and described.

DESCRIPTION

FIG. 1 is a perspective view of the floatable screen and suction device according to the present invention;

FIG. 2 is a side perspective view thereof;

FIG. 3 is a plan view thereof;

FIG. 4 is a front end view thereof;

FIG. 5 is a back end view thereof; and,

FIG. 6 is a side view thereof (the opposite side being a mirror image).
